(57) **CLAIM**

The ornamental design for a mop, as shown and described.

DESCRIPTION

A portion of the disclosure of this patent document contains material which is subject to protection. This patent document may show and/or describe matter which is or may become trade dress of the owner of Trailersphere. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a front and top perspective view of a mop, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged perspective view of detail "9" identified in FIG. 1;

FIG. 10 is an enlarged perspective view of detail "10" identified in FIG. 1;

FIG. 11 is an enlarged perspective view of detail "11" identified in FIG. 2;

FIG. 12 is an enlarged perspective view of detail "12" identified in FIG. 2; and,

FIG. 13 is another perspective view thereof, shown in an alternative position.

The dashed lines in the figures illustrate portions of the mop that form no part of the claimed design. The dash dot dash lines in FIGS. 1, 2, 9, 10, 11 and 12 are for the purpose of illustrating the enlarged views indicators and form no part of the claimed design.
